UNITED STATES PATENT OFFICE

2,606,797

PACKING RETAINER AND LINT ELIMINATOR
FOR RAILWAY JOURNAL BOXES

Fred H. Campbell, Milwaukee, Wis.

Application May 27, 1950, Serial No. 164,650

10 Claims. (Cl. 308—89)

1

This invention relates to packing retainers for railway journal boxes.

In railway journal boxes, a journal bearing resting on a journal is lubricated by oil soaked waste that is contained in the lower portion of the journal box and which bears against and applies lubricant to the lower surface of the journal, and it has long been recognized that the tendency of the waste to travel upwardly into the space between the bearing and the journal has been the cause of bearing failures, hot boxes and the like. In view of this long recognized source of journal box failures, many efforts have been made to afford packing retainers for holding the packing against undesired upward displacement. Such prior packing retainers, however, have been ineffective under many circumstances, have been of such a character as to prevent or retard passage of lubricant, have prevented free re-setting of the packing as is necessary to avoid glazing of the packing, and have been difficult to put in place and have been difficult to remove when required for the purpose of servicing the journal box. The result of this has been that the use of such prior retainers has been relatively limited, and it is, therefore, the primary object to simplify the structure and use of packing retainers for journal boxes and to improve the effectiveness of such retainers. A further and related object of the invention is to afford packing retainers of the aforesaid character that may be readily and easily removed and replaced and which are effectively retained in proper position in the journal box.

While railway journal boxes are relatively well standardized as to form and dimensions, the journal boxes in use on Pullman cars and by certain railways are constructed with a projecting horizontal rib on the inner surface of each side wall somewhat below the axis of the journal, and these ribs have interfered with the use of prior packing retainers. It is, therefore, a further object of the present invention to afford packing retainers that may be used interchangeably in standard journal boxes or in ribbed journal boxes of the aforesaid character, and an object related to the foregoing is to afford such a universal packing retainer that may be employed with equal facility in journal boxes of either type.

In the operation of journal boxes of the aforesaid character, it is found that the waste material utilized as a packing material invariably embodies an appreciable percentage of lint, and this lint tends to follow the rotative movement of the journal and into the space between the bearing

2

and the journal in the same manner as described hereinabove with general reference to the packing material. Such lint is, however, more troublesome insofar as retention may be concerned, in that where means have heretofore been provided for holding the lint against upward travel, such means have had a tendency to gather or collect the lint in a wiping relation to the journal, thus to wip oil from the journal and prevent proper lubrication. It is, therefore, a further object to enable this undesirable action to be eliminated and to enable the gathered lint to be discharged from the retainer to an ineffective position within the journal box.

15 The objectionable tendency of the packing in a journal box to travel upwardly is in many instances aggravated by freezing of moisture or melted snow on the top of the packing during idle or non-running periods when the box becomes cold, and it is a further object of the present invention to retain the waste and lint in journal boxes in such a way that any moisture entering the box in the normal way will be gathered on the retainer rather than on the upper 20 surface of the packing.

Other and further objects of the present invention will be apparent from the following description and claims and are illustrated in the accompanying drawings which, by way of illustration, 25 show a preferred embodiment of the present invention and the principle thereof and what I now consider to be the best mode in which I have contemplated applying that principle. Other embodiments of the invention embodying the same 30 or equivalent principle may be used and structural changes may be made as desired by those skilled in the art without departing from the present invention and the purview of the appended claims.

35 In the drawings:

Fig. 1 is a perspective view showing a journal box equipped with packing retainers embodying the features of the invention;

Fig. 2 is a fragmentary plan view of the wiper 40 element of the retainer;

Fig. 3 is a cross sectional view taken along the line 3—3 of Fig. 2; and

Fig. 4 is a fragmentary vertical sectional view showing the packing retainer of the present invention in use in a ribbed type or Pullman journal box.

For purposes of disclosure, the present invention is disclosed as embodied in waste retainers 45 10R and 10L adapted for individual insertion or removal with respect to railway journal boxes 50 11

or 11P, which are of different types, as will hereinafter be explained. Thus, as shown in Fig. 1, the journal box 11, which is of the most commonly used type, embodies a top wall 12, side walls 13, and an arcuate bottom wall 14 which is sloped upwardly at its outer edge as at 14F so that an outer end opening 15 is defined for the journal box. This opening is closed by a lid 16 that is pivoted at 17 at its upper edge on the outer end edge of the top wall 12. Within the journal box 11, a journal bearing 18 is disposed beneath and in engagement with a conventional wedge 19 that engages the top wall 12, and lateral lugs 20 on the journal bearing 18 have rearwardly facing surfaces that engage the forward faces of locating or side lugs 21 that are formed on the inside surfaces of the side walls 13. It will be noted that the lugs 21 extend downwardly from the top wall 12 and terminate in downwardly and outwardly sloping surfaces 21S that are located somewhat above the horizontal center line of the journal box 11. With respect to the lug 21, it should also be observed that this lug is arranged so that its rear surface is spaced outwardly in an axial sense from the usual rear wall or dust guard mounting of the journal box, and this rearwardly facing surface of the lug 21 is utilized in accordance with the present invention in locking the packing retainers 10R and 10L releasably in position in the journal box.

The journal bearing 18 is of the usual or standard type and is arranged to bear on a cylindrical bearing surface 25B of a journal 25, and this journal 25 may have the customary outer flange 25F, which may, under certain circumstances, engage with the end of the journal bearing 18.

In the use of the journal box arrangement shown in Fig. 1, the lower portion of the journal box is filled with oil-soaked material, such as waste 26, and this waste engages the lower portion of the bearing surface 25B so that this bearing surface is lubricated in the course of rotation of the journal 25. In such rotation, however, there is a tendency for the waste or packing 26 and the lint that is invariably included therein, to travel upwardly and into the bight between the bearing surface 25B and the journal bearing 18 to cause a condition usually termed a waste grab, and it is to prevent such upward displacement of the waste 26 and lint that the packing retainers 10R and 10L are utilized. It will be noted that the packing retainers 10R and 10L are of identical construction except that they are made as right and left-hand members so as to be adapted for location in the journal box on opposite sides of the journal 25. Thus, for present purposes, only one of the packing retainers will be specifically described, it being understood that the other packing retainer is identical except for reversal of the positions of the parts to adapt it for use on the other side of the journal 25.

As shown in Fig. 1 of the drawings, the packing retainer 10R is formed by upper and lower legs 28A and 28B that are formed from a single piece of spring material, as will hereinafter be described in some detail, and the upper leg 28A is arranged to constitute a positioning and releasable locking member while the lower leg 28B serves as a carrier for a toothed pressure or wiping member 29 that has spaced teeth 29T thereof held with their ends in wiping engagement with the bearing surface 25B throughout the length of the bearing surface, as will be described in some detail hereinafter. The arrangement is

such that the wiping member 29 is disposed against or slightly above the top surface of the packing or waste 26, thereby to prevent upward travel of the waste and lint material with the bearing surface 25B in the rotation of the journal 25. As will hereinafter be described in detail, the toothed wiping member 29 has a unique action in respect to its retaining function as well as in eliminating the objectionable contact of collected lint with the journal.

Under and in accordance with the present invention, the legs 28A and 28B of the packing retainer 10R are so related one to the other that the packing retainer may be readily inserted or removed from the journal box, thereby to facilitate proper and effective servicing of the journal box as, for instance, when removal and replacement of the packing 26 is required, or when inspection of the packing retainer 10R is to be made. In accomplishing this result, the elongated spring wire element that forms the legs 28A and 28B is formed with a torsion coil 28C, which in the present instance comprises substantially one and one-half turns in the coil and from opposite ends of the torsion coil 28C, the spring wire element is extended to afford operating arms 30A and 30B that extend generally upwardly in a slightly divergent relationship, as will be evident in Fig. 1. Thus, the arms 30A and 30B are disposed in substantially a common plane, the arm 30A being slightly offset as at 130A to compensate for the axial dimension of the torsion coil 28C. At their upper ends, the arms 30A and 30B are extended integrally and at similar angles of somewhat over 90° to afford the legs 28A and 28B, and it will thus be observed that the arms 30A and 30B, together with the torsion coil 28C, constitute what amounts to a handle that extends in a downward and slightly forward direction with respect to the legs 28A and 28B, thereby to facilitate grasping of the retainer by a worker when the lid 16 of the journal box is opened.

When the handle element is thus grasped, the arms 30A and 30B may be pressed toward each other, and this will bring the leg 28A downwardly toward a parallel relationship with respect to the legs 28B, and when the legs are in this closely spaced relationship, the packing retainer may readily be moved into or removed from the journal box 11, the leg 28A in such an instance moving beneath the element or lower end surface 21S of the side lug 21 of the journal box. When the packing retainer is in a fully inserted position within the journal box, the handle of the retainer is released so that the arms 30A and 30B separate, and the upper leg 28A is pivoted in an upward direction to the position shown in Fig. 1 of the drawings. When this is done, the leg 28A is disposed in what might be termed a locking or holding relationship with respect to the side lug 21 of the journal box. In accomplishing this locking action, the upper leg 28A is offset as at 128A generally toward the axis of the journal 25 and in a plane that is perpendicular to the plane of the arms 30A and 30B. The leg 28A is then extended as at 228A, and at its end has a retaining finger 328A that is arranged to engage the inner or rear edge of the side lug 21 of the journal box. When the parts assume this relationship, the intermediate portion 228A of the upper arm engages the lower surface of the side lug 21, and the result is that the forces are applied through the arms 30A and 30B so that the lower leg 28B

is held yieldingly in a downward direction. The dimensions are such that the lower surface of the torsion coil 28C engages the rounded surface of the journal box bottom wall 14, thereby to apply at the same time a yielding force which maintains the ends of the teeth 29T in engagement with the bearing surface 25B of the journal 25.

The wiping member 29 is formed from a sheet of a material such as brass, which has good bearing properties with respect to the steel of the journal, and this sheet of material is bent upon itself, as shown in Figs. 2 and 3, to afford a looped edge 129 and a tube edge 229 with an intermediate flat or thin portion 329 that is of double thickness and which is secured together by spaced rivets 40. The toothed wiping edge is afforded by the looped portion 129 of the sheet metal member, and the teeth 29T are formed by cutting away intermediate slots 41 so that each tooth constitutes an individual loop that is spaced from the next adjacent loop. These loops are, however, under the present invention, given a special formation in order that disposal of collected lint may be effected and the waste retaining action thereof on the journal bearing surface 25B may be enhanced without preventing passage of lubricant with the journal surface. Thus, each of the teeth is slightly twisted, as will be evident in Figs. 2 and 3, and this serves to reduce the effective spacing between the teeth 29T and also serves to present an angular lower surface which it has been found tends to reduce the clinging of the lint and waste material to the teeth. In other words, there is a tendency for the rotation of the journal 25 to displace the waste and lint material endwise with respect to the teeth 29T while at the same time such teeth tend to hold the waste against upward movement with the journal bearing surface. Moreover, the teeth 29T are so related and spaced that after a particle of lint has been displaced longitudinally by the angular lower surface of a tooth, it comes into alignment with an upwardly and angularly disposed space, as well as with the open space within the loop of the adjacent tooth, and it is found that such lint does not follow or travel up with the journal surface, but is discharged upwardly and away from the journal so as to come to rest in position on and adjacent to the rear portion 229 of the member 29. The exact path of travel of such lint is not known, but it has been determined that it results from the twisted and looped formation of the spaced teeth 29T, for when the loop or the twist is not employed, such disposal of the lint is not attained.

The tubular portion 229 of the wiping member 29 serves as the mounting means for associating the member 29 with the lower leg 28B of the retainer. Thus, the tubular portion 229 is generally rectangular in cross sectional form, as shown in Figs. 1 and 4 of the drawings, and the lower leg 28B is inserted into this tubular portion 229 and is interlocked therewith in a rotative sense as well as a longitudinal sense. To attain this interlocking action, the lower leg 28B is offset as at 228B in a plane that is perpendicular to the plane of the arms 30A and 30B, and the dimension of this offset is such that the offset portion engages one side of the tubular portion 229 while the other portions of the member 28B engage the opposite side of the tubular portion 229. Hence, when the member 28B is fully inserted in the tubular portion 229, the parts are held in a predetermined rotative relationship so that the teeth 70

29T will project in a generally horizontal plane toward the axis of the journal 25, and the member 29 is held in predetermined longitudinal position on the lower leg 28B by forming indentations 43 in the sides of the tubular portion 229 so as to engage with oppositely facing surfaces of the offset portion 228B.

In Fig. 4 of the drawings there is illustrated the form of journal box 11P that is normally used by some railways and in Pullman cars, and this journal box is quite similar to the aforesaid journal box 11 except that the lug 21 is formed as a hollow lug 121, and somewhat below the location of the axis of the journal 25, a horizontal rib R is formed along each inner surface of the side walls of the box. The packing retainer of the present invention is adapted for use with equal facility with the journal box 11P, as will be evident in Fig. 4 of the drawings, the wiping member 29 in such an instance being disposed immediately below the rib R while the upper leg 28A cooperates with the side lug 121 in the identical manner hereinbefore described.

It will be apparent that due to the twisted and looped formation of the teeth 29T, a substantially continuous metallic barrier is provided over most of the upper surface of the packing material, this being particularly true in the area that is directly adjacent to the bearing surface of the journal. Hence, when moisture enters the journal box, as, for example, when snow blows into a partially open journal box, this snow and the moisture produced in the melting thereof will be deposited on the retaining member 29 and the teeth 29T thereof. Hence, if the journal box becomes sufficiently cold to cause freezing of such moisture, this freezing will take place primarily on the various metal surfaces of the retainer and not upon the top of the waste material. This has been found to reduce the tendency that would normally be present for the waste material to become stiff and to move upwardly as a body with the journal surface.

In the use of the present retainer, the angular positioning of the looped and spaced teeth serves to effectually retain the waste against upward movement, and serves to dispose of the lint material in the manner hereinbefore described, and in attaining this action, and particularly with respect to the discharge of the lint upwardly and away from the journal surface, the present retainer avoids any tendency to wipe the oil from the journal surface. Thus, the oil may move freely up with the journal surface so as to attain proper lubricating action.

From the foregoing, it will be evident that the present invention eliminates many of the difficulties that have heretofore been encountered where efforts have been made to utilize waste retainers in journal boxes. It will also be evident that the present retainer disposes of collected lint in such a way that this lint does not wipe the journal bearing and thus prevent proper lubrication thereof, and it will also be clear that through the formation of the looped and twisted teeth, the upper surface of the packing material is protected against the objectionable results that would normally be caused by freezing of the moisture on the upper surfaces of the packing.

It will also be evident that with the packing retainer of the present invention, the waste in the journal box may be reset quickly and easily without removal of the packing retainer, and thus the avoidance of glazing of the packing is rendered quite simple.

From the foregoing description, it will also be evident that the present invention affords a packing retainer that may quickly and easily be placed in position in or removed from the journal box, and that this packing retainer is universal in character in that it may be employed with equal facility in different types of journal boxes that are now in use.

Thus, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim:

1. In a packing retainer and lint eliminator for a journal box in which a journal having a cylindrical bearing surface is positioned, an elongated wiper element adapted to be positioned on top of the packing in such a box with one edge of the element extended longitudinally along and in wiping contact with the bearing surface of the journal, said element comprising a plurality of laterally projecting spaced teeth along said edge and formed from sheet metal to afford each tooth as a loop of sheet metal with the loop slightly twisted to afford angular surfaces for cooperation with the moving bearing surface of a journal to displace and promote discharge of any lint gathered beneath such teeth.

2. In a packing retainer and lint eliminator for a journal box in which a journal having a cylindrical bearing surface is positioned, an elongated wiper element adapted to be positioned on top of the packing in such a box with one edge of the element extended longitudinally along and in wiping contact with the bearing surface of the journal, said element comprising a plurality of laterally projecting spaced teeth along said edge and formed from sheet metal to afford each tooth as a loop of sheet metal with the loop slightly twisted to afford angular surfaces for cooperation with the moving bearing surface of a journal to displace and promote discharge of any lint gathered beneath such teeth, and releasable resilient mounting means carrying said wiping element for mounting such element in a journal box.

3. In a packing retainer for journal boxes, an elongated wiping element comprising a sheet of metal bent upon itself to afford a loop along one edge and having spaced transverse slots extended inwardly from said edge to define spaced teeth afforded by said loop, and said teeth being uniformly twisted to afford angularly disposed faces on the teeth and form the spaces between the teeth at an angle.

4. A device according to claim 2 in which said mounting means comprises a mounting member formed from a single length of spring wire to afford a torsion coil with spaced operating arms extending from opposite ends of the coil in substantially the same plane to define an outer handle portion to be grasped by a user, one of said arms having a lower leg extended therefrom in said plane and at a predetermined angle to said one arm of somewhat more than ninety degrees but substantially less than one-hundred eighty degrees, and in which said wiper element is fixed on said lower leg so that the spaced projecting teeth thereof extend in one direction therefrom in a second plane substantially normal to said first mentioned plane, an upper leg integrally extended in said first mentioned plane from the

other of said arms so as to normally diverge with respect to said lower leg, said upper leg being formed to afford an offset portion adapted to extend around the side lug in a journal box and having a retaining finger extending in a third plane perpendicular to said first mentioned plane and in a direction opposite to said one direction to engage the edge of such a lug remote from the open end of a journal box to hold the retainer in place in such journal box.

5. In a packing retainer for journal boxes, a mounting member formed from a single length of spring wire to afford a torsion coil with spaced operating arms extending from opposite ends of the coil in substantially the same plane to define an outer handle portion to be grasped by a user, one of said arms having a lower leg extended therefrom in said plane and at a predetermined angle to said one arm of somewhat more than ninety degrees but substantially less than one-hundred eighty degrees, a pressure member formed from sheet metal and mounted on said lower leg and having spaced projecting teeth extending in one direction in a second plane substantially normal to said first mentioned plane, an upper leg integrally extended in said first mentioned plane from the other of said arms so as to normally diverge with respect to said lower leg, said upper leg having a retaining finger extending laterally therefrom in position to engage the edge of such a lug remote from the open end of a journal box to hold the retainer in place in such journal box.

6. In a packing retainer for journal boxes, a mounting member formed from a single length of spring wire to afford a torsion coil with spaced operating arms extending in a gradually diverging relation from opposite ends of the coil in substantially the same plane to define an outer handle portion to be grasped by a user, one of said arms having a lower leg extended therefrom in said plane and at a predetermined angle to said one arm of somewhat more than ninety degrees, said lower leg having an offset portion intermediate its ends in a second plane normal to said first mentioned plane, a pressure member formed from sheet metal to afford an elongated flat tube embracing and interlocked with said offset portion of said lower leg and having spaced projecting teeth extending in one direction in said second plane, an upper leg integrally extended in said first mentioned plane from the other of said arms at an angle corresponding substantially to said predetermined angle so as to normally diverge with respect to said lower leg, said upper leg being formed to afford an offset portion adapted to extend around the side lug in a journal box and having a retaining finger extending in a third plane perpendicular to said first mentioned plane and in a direction opposite to said one direction to engage the edge of such a lug remote from the open end of a journal box to hold the retainer in place in such journal box.

7. In a packing retainer for journal boxes, a mounting member formed from a single length of spring wire to afford a torsion coil with spaced operating arms extending from opposite ends of the coil in substantially the same plane to define an outer handle portion to be grasped by a user, one of said arms having a lower leg extended therefrom in said plane and at a predetermined angle to said one arm of somewhat more than ninety degrees but substantially less than one-hundred eighty degrees, said lower leg having an offset portion intermediate its ends in a second

plane normal to said first mentioned plane, a pressure member formed from sheet metal to afford an elongated flat tube embracing and interlocked with said offset portion of said lower leg and having spaced projecting teeth extending in one direction in said second plane, an upper leg integrally extended in said first mentioned plane from the other of said arms so as to normally diverge with respect to said lower leg, said upper leg being formed to afford an offset portion adapted to extend around the side lug in a journal box and having a retaining finger extending in a third plane perpendicular to said first mentioned plane and in a direction opposite to said one direction to engage the edge of such a lug remote from the open end of a journal box to hold the retainer in place in such journal box.

8. In a packing retainer for journal boxes, a mounting member formed from a single length of spring wire to afford a torsion coil with spaced operating arms extending from opposite ends of the coil in substantially the same plane to define an outer handle portion to be grasped by a user, one of said arms having a lower leg extended therefrom in said plane and at a predetermined angle to said one arm of somewhat more than ninety degrees but substantially less than one-hundred eighty degrees, a pressure member formed from sheet metal to afford an elongated flat tube embracing and interlocked with said lower leg and having spaced projecting teeth extending in one direction in a second plane substantially normal to said first mentioned plane, an upper leg integrally extended in said first mentioned plane from the other of said arms so as to normally diverge with respect to said lower leg, said upper leg being formed to afford an offset portion adapted to extend around the side lug in a journal box and having a retaining finger extending in a third plane perpendicular to said first mentioned plane and in a direction opposite to said one direction to engage the edge of such a lug remote from the open end of a journal box to hold the retainer in place in such journal box.

9. In a packing retainer for journal boxes, a mounting member formed from a single length of spring wire to afford a torsion coil with spaced operating arms extending from opposite ends of the coil in substantially the same plane to define an outer handle portion to be grasped by a user, one of said arms having a lower leg extended therefrom in said plane and at a predetermined angle to said one arm of somewhat more than

ninety degrees but substantially less than one-hundred eighty degrees, a pressure member formed from sheet metal to afford an elongated flat tube embracing and interlocked with said lower leg and having spaced projecting teeth extending in one direction in a second plane substantially normal to said first mentioned plane, an upper leg integrally extended in said first mentioned plane from the other of said arms so as to normally diverge with respect to said lower leg, said upper leg having a retaining finger extending laterally therefrom in position to engage the edge of such a lug remote from the open end of a journal box to hold the retainer in place in such journal box.

10. In a packing retainer for journal boxes, a mounting member formed from a single length of spring wire to afford a torsion coil with spaced operating arms extending in a gradually diverging relation from opposite ends of the coil in substantially the same plane to define an outer handle portion to be grasped by a user, one of said arms having a lower leg extended therefrom in said plane and at a predetermined angle to said one arm of somewhat more than ninety degrees, a pressure member formed from sheet metal mounted on said lower leg and having spaced projecting teeth extending in one direction in a second plane that is substantially normal to said first mentioned plane for wiping engagement with the bearing surface of a railway journal, an upper leg integrally extended in said first mentioned plane from the other of said arms at an angle corresponding substantially to said predetermined angle so as to normally diverge with respect to said lower leg, said upper leg being formed to afford a retaining finger extending in a third plane perpendicular to said first mentioned plane and in a direction opposite to said one direction to engage the edge of such a lug remote from the open end of a journal box to hold the retainer in place in such journal box.
